(57) **CLAIM**

The ornamental design for a rail joiner, as shown and described.

DESCRIPTION

FIG. 1 is a top and front perspective view of part A of the rail joiner, showing half of my new design;

FIG. 2 is a rear perspective view of part A of the design illustrated in FIG. 1;

FIG. 3 is a top and front perspective view of part B of the rail joiner, showing the other half of my new design;

FIG. 4 is a rear perspective view of the part B of the design;

FIG. 5 is a top and front perspective view of the design assembly with part A and part B in a 180° configuration;

FIG. 6 is a rear perspective view of the design assembly with part A and part B in a 180° configuration;

FIG. 7 is a top plan view of the design assembly with parts A and B in a 180° configuration;

FIG. 8 is a top and front perspective view of the design assembly with parts A and B in a 90° configuration;

FIG. 9 is a top plan view of the design assembly with parts A and B in a 90° configuration;

FIG. 10 is a rear perspective view of the design assembly with parts A and B in a 90° configuration;

FIG. 11 is a bottom plan view of the design assembly with parts A and B in a 270° configuration;

FIG. 12 is a top and front perspective view of the design assembly with parts A and B in a 270° configuration; and,

FIG. 13 is a rear perspective view of the design assembly with parts A and B in a 270° configuration.
